PISTON

John P. Butterfield, Grosse Pointe Woods, Mich.,
assignor to Chrysler Corporation, Highland
Park, Mich., a corporation of Delaware

Application December 15, 1950, Serial No. 201,032

15 Claims. (Cl. 309—10)

1

This invention relates to internal combustion engines of the double acting type and is primarily concerned with the pistons used in such engines and the piston mounted slideway means employed to connect the pistons of such engines to the associated engine crankshaft. This invention represents an improvement on the piston construction disclosed in my co-pending application, Serial No. 133,926 filed December 19, 1949.

In the double acting type of engine a double-ended piston is usually employed for reciprocatory movement in each engine cylinder bore, such engines being arranged to provide a combustion chamber at each end of each cylinder bore for cooperation with each end of the double-ended piston mounted therein. Engines of this general type are known in the art and employ a crankshaft which usually extends through and is generally connected to the double-ended piston by means other than a connecting rod such as is employed in the more conventional type of internal combustion engine. For a more detailed description of this particular type of engine, see the copending applications of A. G. Herreshoff, Serial No. 16,801, filed March 24, 1948, now Patent No. 2,613,651, issued October 14, 1952 and Serial No. 84,081 filed March 29, 1949, now Patent No. 2,581,326 issued January 1, 1952, the applications of John P. Butterfield, all filed March 24, 1948, Serial No. 16,645, now Patent No. 2,610,615 issued September 16, 1952, Serial No. 16,646, now Patent No. 2,595,761, issued May 6, 1952; Serial No. 16,647, now Patent No. 2,571,198 issued October 16, 1951; Serial No. 16,648, now Patent No. 2,603,538 issued July 15, 1952; Serial No. 16,649 now Patent No. 2,614,009 issued October 14, 1952, and Serial No. 16,650 and Serial No. 133,926, filed December 19, 1949, and the application of A. J. Slemmons, Serial No. 80,729, filed March 10, 1949, now Patent No. 2,588,666 issued March 4, 1952.

The double acting type of engine offers many advantages over the more conventional types of engines but certain difficulties in the manufacture, assembly and operation of such an engine have heretofore been deemed to be of such a bothersome or supposedly insurmountable character as to discourage the use of this type of engine.

One of the difficulties experienced with the double-acting type of engine has been in providing a practicable operating connection between the pistons and engine crankshaft which connections must provide a means for controlling

2

the clearances between the connected pistons and crankshaft and also provide a means for distributing the bearing loads more or less uniformly over the surfaces of the piston slideways that are slidably engaged by the crankshaft bearing block.

It is a primary object of this invention to provide an internal slideway type of piston having a structural arrangement that permits accurate control of the temperature variable working clearances between the elements slidably engaged with the piston.

It is a further object of this invention to provide a piston construction wherein the piston skirt and the portions of the piston head connected thereto are connected by a strut member that effectively controls the thermal expansion of the piston during engine operation and also provides a means for controlling the bearing block slideway stress distribution.

It is another object of this invention to provide a composite double-ended, internal slideway type of piston formed in such a manner and formed from such materials that the thermal expansion and contraction as well as the working clearances between the associated elements may be accurately controlled.

It is another object of this invention to provide a piston construction with an interiorly disposed slideway adapted to be slidably engaged by a crankshaft bearing block wherein the slideway and support therefor are formed in a manner adapted to distribute the bearing block loads more or less uniformly over the bearing block engaged surfaces of the slideway to thereby reduce the unit pressures on these engaged parts during engine operation.

Further objects and advantages of my invention reside in the novel combination and arrangement of parts hereinafter described and disclosed in the accompanying drawings in which:

Fig. 1 is a transverse sectional elevational view through a double acting engine cylinder block structure showing a crankshaft connected by a bearing block to a slideway of a piston embodying my invention;

Fig. 2 is a sectional plan elevation of the structure shown in Fig. 1, the view being taken as indicated by the reference line 2—2 of Fig. 1;

Fig. 3 is an enlarged side elevational view of the piston structure shown in Figs. 1 and 2;

Fig. 4 is a fragmentary sectional elevational view of one head portion of the piston shown in Fig. 3, the view being taken along the line 4—4 of Fig. 3;

Fig. 5 is a sectional elevational view of one head portion of the piston shown in Figs. 1-4, the view being taken along the reference line 5-5 of Fig. 3; and

Figs. 6, 7 and 8 are side, plan and end elevational views respectively of the strut member that is imbedded in the piston heads of a piston embodying this invention.

In general, the engine utilizing pistons of the type embodying this invention comprises a cylinder block structure A formed of component or complementary half portions 10 and 11 having planar face contact in a plane 12-12 which is vertical for the illustrated positioning of the engine in Fig. 1. Each portion of the cylinder block structure A is formed with a half-part of a cylinder 13 of substantially uniform diameter extending between the opposite side faces 14 of the block structure A. Each exposed end of the cylinder 13 is closed by a cylinder head 15 providing a combustion chamber 16. Suitable intake and exhaust valves (not shown) control inlet of the fuel mixture to the combustion chambers 16 and discharge of the exhaust gas from said combustion chambers. Combustion chamber fuel ignition means such as the spark plugs 17 are provided although other types of fuel ignition may be used.

The cylinder block portions 10 and 11 are brought together and the cylinder heads 15 maintained in their illustrated assembled positions by a plurality of through bolt assemblies 19 which extend through the block portions and cylinder heads. For an engine of the circulating liquid cooled type, as illustrated, the cylinder heads 15 and block portions 10, 11 are provided with cored intercommunicating coolant passages 34.

Reciprocating within the typical illustrated cylinder 13 is a piston structure B having a head portion 35 at each end thereof arranged to cooperate with the combustion chambers 16 of the cylinder heads 15. The piston structure B carries a set of rings 36 adjacent each of its head portions 35 and the oppositely disposed piston head portions 35 are connected together by an intermediate slotted, tube-like, skirt structure 37 herein illustrated as comprising cylindrical end portions connected by a plurality of circumferentially spaced piers or tie-portions 38. The piston skirt portion 37 is connected to the associated head portions 35 at a pair of diametrically disposed locations by screw or bolt connections 71 that are more fully described below.

The skirt portion 37 of piston structure B is provided with two pairs of diametrically disposed, axially extending openings or slots 45 and 46, respectively, which slots are bounded circumferentially of the piston by the piers 38. The slots 45 are adapted to receive the crankshaft 22 and to accommodate reciprocation of the piston structure B relative to the crankshaft 22. Crankshaft 22 is rotatable about its axis 40, on its journal portions 47 that are mounted in bearings 48 carried by semi-cylindrical bearing openings 49 formed in the opposed inner faces of the cylinder block portions 10 and 11. The slots 46, which are circumferentially rotated ninety degrees from the slots 45 (see Figs. 1 and 3), are adapted to receive the end portions of the internal, transversely extending, opposed piston slideways 51 that depend from each piston head inner surface.

Associated with each cylinder and its contained piston structure is a cylindrical crankpin

portion 23 of the crankshaft 22. Each crankpin portion 23 is connected to an adjacent pair of crankshaft journal portions 47 by the obliquely extending crankshaft web portions 24. The crankpin 23 and the oblique connecting web portions 24 are continuously disposed within the hollow chamber formed interiorly of piston skirt structure 37 intermediate the heads 35 of the double-ended piston B.

The force transmitting connection between each piston structure B and the crankshaft 22 comprises the internal, opposed, slideways or bearing block guides 51 that are carried by the free ends of the flanges 54 and 55 that depend from the inner side or face of each piston head portion 35. Slideways 51 slidably receive therebetween a bearing block D operatively carried by and rotatably mounted on the crankshaft crankpin 23. The connected parts 51, D and 23 are so constructed and arranged as to provide a sliding, rockable bearing connection between the piston structure B and the crankshaft crankpin 23.

The spaced apart, opposed, piston head carried, bearing block slideway portions 51 are preferably cast as portions of the piston heads 35 as will be more fully explained in the subsequent description. Slideways 51 are connected to the heads 35 by the depending piston head flanges or webs 54 and 55. The webs 54 are aligned with and sweep into the associated guideway portions 51 in a manner that supports the slideways 51 as more or less rigid parts of the piston head structures 35. The webs 55 are disposed at right angles to the webs 54 and provide additional support for the slideways 51. By the arrangement shown the slideway portions 51 are thus spaced from each other in a direction axially of the piston structure and present opposed, arcuately-shaped bearing surfaces 53 facing each other. Each slideway bearing surface 53 is a portion of a cylindrical surface which is adapted to slidably and rockably engage a mating cylindrically formed bearing surface on the crankshaft bearing block D. Bearing block D may be of any of the forms specifically described in the aforementioned A. J. Slemmons application Serial No. 80,729, now Patent No. 2,588,666 issued March 4, 1952. As will be seen from Figs. 1 and 3 the slideways 51 extend transversely through the piston, the opposite ends of the slideways 51 being open and disconnected from the piston skirt portion 37, that is directly supported by a head web 54. Each piston head web portion 54 extends the full length of the associated slideway 51 and is flared out (see Figs. 2 and 4) at its inner end to cover the full width of the slideway 51. As it is practically essential to arrange the slideway supporting web portion 54 of a double ended piston so that it extends along and is aligned with the central portion 58a (see Fig. 4) of the slideway 51, it has been found that in conventional constructions of this type, using solid, centrally arranged, slideway supporting, web portions 54, the solid webs provide the slideways 51 with a relatively high stress concentration and a maximum rigidity along the central portion 58a (see Fig. 4) of the bearing surface 53 while the edge or side portions 58b of the slideway bearing surfaces 53, which are somewhat flexible relative to the portions 58a, are very lightly stressed during engine operation. When a solid web member is used to support the slideway 51 it has been found that the increased rigidity and relatively high, non-uniform

form, stress concentration across the width of the bearing surface 58 during engine operation has a tendency to unnecessarily increase wear along the central portions 58a of the slideways and to even cause the slidably engaged bearing block D and the slideways 51 to seize and cause engine destruction. The high stress concentration and increased rigidity along the central portions 58a of the slideways further prevent maintenance of the necessary lubricating film across the entire width of the bearing surfaces 58 of the slideways and this increases engine wear and reduces the impact cushioning properties of the lubricant film. A more detailed discussion of this stress concentration problem along the slideway bearing surfaces 58 is contained in my co-pending application Serial No. 132,926.

In addition to the undesirable slideway stress concentrations resulting from forming the slideway supporting webs 54 as solid masses of the piston head material, it has also been found that such constructions produce undesirable thermal expansions in certain parts of the piston that make it very difficult, if not impossible, to accurately control the clearances between the piston and the elements slidably engaged therewith such as the bearing block element D and the walls of the cylinder bore 13. In conventional piston constructions of the type herein generally disclosed, the slideway supporting webs 54 and 55 are usually cast as an integral, solid portion of the piston head 35. Accordingly, the heat of fuel combustion in chambers 16, that is applied to the heads 35, is freely and quickly transmitted to all portions of the piston heads 35 and to the attached skirt 37 and this results in both axial and diametrical thermal expansion of the piston heads 35 and skirt 37. Axial thermal expansion of heads 35 causes the opposed slideways 51 to move closer together and this increases the bearing pressures on the bearing surfaces of the bearing block D. Diametrical expansion of the piston heads 35 causes the heads 35 to enlarge and reduce the clearances between the sides of the piston B and the walls of the cylinders 13. Axial thermal expansion of the skirt 37 will tend to move the heads 35 apart and thereby open up clearances between the slideway surfaces 58 and the engaged bearing block D. Likewise, diametrical thermal expansion of the skirt 37 will move the skirt 37 closer to the walls of the cylinder bore 13. It is thought to be obvious from the foregoing explanation that it is necessary to leave considerable clearance between the bearing block slideways 51 and the bearing block D and also between the sides of the piston B and the cylinder bores 13 to compensate for the various thermal expansions that occur in the pistons B during engine operation.

Also, in the usual double-ended piston construction the skirt 37 is connected to the piston heads 35 around the complete periphery of the piston. This provides a ready path of heat flow from the heads 35 to the skirt 37 and tends to increase both diametrical as well as axial thermal expansion of the skirt portion 37. As the piston heads 35 are usually of aluminum or similar material of high thermal conductivity while the skirt 37 is usually of steel or a similar low thermal conductivity material, it can be seen that skirt 37 may elongate and expand at one rate while the heads 35 will expand and elongate at a different rate. This just further

complicates the control of the clearances between the piston B and the several elements slidably engaged therewith, such as the bearing block D and the walls of the cylinder bores 13. It will be observed from a study of Figs. 4 and 5 that the piston heads 35 in this construction are connected to the skirt portion 37 by the strut 60 along two relatively short, diametrically disposed, peripheral portions and that there is a clearance or insulating space 59 between the heads 35 and the skirt 37 around the majority of the piston periphery. Such an arrangement materially reduces the heat flow to and thermal expansion of the skirt 37 and provides for a more accurate control of the clearances between the piston B and its slidably engaged elements. The specific type of connection between the piston heads 35 and the skirt 37 will now be described in connection with the novel piston head construction embodying this invention.

Figs. 6, 7 and 8 disclose a strut member 60 that is integrally cast in each piston head 35. The strut member 60 serves a dual function of first providing a more or less uniform stress concentration across the bearing surfaces 58 of the slideways 51 and secondly providing a means for accurately controlling the thermal expansion of the piston heads 35 and piston skirt portion 37. The strut 60 is cast in the piston head 35 so that it forms the back bone of and extends centrally along the slideway supporting web 54. Strut 60 comprises a plate-like body portion 61, having a wing-like, transversely extending, enlarged, anchor head portion 62 formed along the upper portion thereof and an enlarged, tubular, longitudinally extending, formation 63 formed along the lower portion thereof. The upper anchor portion 62 is formed with a plurality of slots 64 that provide a degree of flexibility in the anchor head 62 so that thermal expansion of the piston will not cause cracking of the piston head 35. The slots 64 also fill with head material during the head casting process so as to securely anchor the strut 60 in the head material. The body portion 61 and the tubular lower portion 63 are each provided with a series of holes 65 and 66 respectively, which holes fill with the head material during the piston head casting process to provide another means for securely anchoring the strut member 60 in the head 35. Head material that flows through the holes 66 in the lower tubular member 63 may fill a portion of the bore 67 in the tubular member 63. However, during the final machining of the piston B the bore 67 is drilled to remove any head material that might be lodged therein. On each end of the strut body portion 61, there is formed a transversely extending, wing-like, flange 68. Flanges 68 provide an improved means for connecting the piston heads 35 to the piston skirt 37. It will be noted from Fig. 5 that the flanges 68 of strut 60 are the only portions of the piston head 35 that are in actual contact with the piston skirt 37, therefore the flow of heat from the heads 35 to the skirt 37 is materially reduced from that occurring with a conventional double ended piston construction wherein the piston heads engage the piston skirt around the entire circumference of the piston. It will be noted that the strut end flanges 68 are of a width that is no greater than the width of the slideway bearing surfaces 58. As a result of this relatively limited contact area between the strut end flanges 68 and the skirt 37 there is only a minor heat flow from the piston heads

35 to the piston skirt 37. Furthermore, as the strut 60 is preferably formed from the same low thermal conductivity material as the piston skirt 37, such as steel or the like, the heat flow to the piston skirt from the piston head in this construction is kept to a minimum.

The connection of the piston heads 35 to the piston skirt 37 is preferably by means of screws 71 (see Fig. 5) although other types of equivalent connections may be used. If the screws 71 are used the strut flanges 68 and the adjacent portions of the piston head 35 are bored and threaded to receive the threaded shanks of the screws 71. The piston skirt 37 is also bored to provide a shoulder formation 72 against which the heads of the screws 71 may bear. The screws 71 originally have a head formation 73 (see Fig. 5) with an intermediate necked portion 74. As the screws 72 are threaded into the tapped bores in the strut flanges 68 and into the heads 35 sufficient torque is applied to the heads 73 to twist off the heads 73 outwardly of the necked portions 74 and the remaining portions of the screw heads 73 that thereafter project outwardly beyond the skirt 37 are then cut off during final machining of the piston B.

From the above description of the strut member 60 and its arrangement in the piston structure B, it is thought to be obvious that the tubular bore 67 of the strut lower portion 63 provides the necessary flexibility in the slideway supporting web 54 to more or less uniformly distribute the bearing block stresses across the full width of the slideway surfaces 58 as more fully explained in my co-pending application Serial No. 133,926, filed December 19, 1949. Furthermore, strut member 60 provides a means for controlling the heat flow from the piston heads 35 to both the piston skirt 37 and the piston slideways 51. Not only is the heat flow from the heads 35 controlled but the resulting thermal expansion of the piston B is controlled and in this manner the required clearances between the several elements slidably engaged with the piston may be reduced without danger of parts seizure. Accordingly, quieter and more efficient engine operation results from the use of pistons embodying this invention. By using the steel strut members 60 to connect the aluminum piston heads 35 to the steel piston skirt 37, it will be noted that a complete ring of similar material, steel in this case, is utilized to connect and more or less insulate the heated piston heads 35 from the slideable, steel, crankshaft bearing block D. This arrangement thus provides a connection between the crankshaft throw 23 and the piston B that is substantially of the same material and thus the thermal expansions and contractions of these connected elements are of the same degree and working clearances between these engaged elements may be most accurately controlled. It is thought that the arrangement disclosed is such that heat that is applied to the piston heads 35 will cause thermal expansion of the aluminum heads 35 in an axial direction that will be outwardly from rather than inwardly towards the slideways 51 and thus the operating clearances between the slideways 51 of the piston B and the bearing block D will be practically unaffected during engine operation. The only contact between the aluminum piston heads 35 and the steel bearing block D is at the portions 35a of the piston heads located between the slideway surfaces 58 and the inner ends 63 of the struts 60. However, as

the steel strut 60 acts as a heat dam between the heads 35 and the portions 35a the heat transferred to the portions 35a is negligible and thus the working clearances are unaffected.

5 I claim:

1. A piston comprising a head portion and an encircling, depending, skirt portion, a web depending from the inner surface of said head portion, a bearing block slideway supported from

10 the free end of said web and arranged to extend transversely of said skirt portion but disconnected therefrom, said web having a bore extending therethrough in a direction longitudinally of and adjacent the slideway, said web having relatively limited portions adjacent each end thereof connected to said skirt portion and providing the only contact between said head and said skirt portion.

2. A piston comprising a head portion and an

20 encircling, depending, skirt portion, a web depending from the inner surface of said head portion, a bearing block slideway supported from the free end of said web and arranged to extend transversely of said skirt portion but disconnected therefrom, said web having a bore extending therethrough in a direction longitudinally of and adjacent the slideway, said web having

25 portions adjacent each end thereof connected to said skirt portion and providing the only contact between said head and said skirt portion.

3. A piston comprising a head portion and an encircling, depending, skirt portion, a web depending from the inner surface of said head portion, a bearing block slideway supported from the free end of said web and arranged to extend transversely of said skirt portion but disconnected therefrom, said web having a bore extending therethrough in a direction longitudinally of and adjacent the slideway, said web having

30 portions adjacent each end thereof connected to said skirt portion and providing the only contact between said head and said skirt portions, said web end portions extending along the periphery of the skirt portion for distances no greater than the width of said slideway.

3. A piston comprising a head portion and an encircling, depending, skirt portion, a web depending from the inner surface of said head portion, a bearing block slideway supported from the free end of said web and arranged to extend transversely of said skirt portion but disconnected therefrom, said web having a bore extending therethrough in a direction longitudinally of and adjacent the slideway, said web having

40 portions adjacent each end thereof connected to said skirt portion and providing the only contact between said head and said skirt portions, said web end portions extending along the periphery of the skirt portion for distances no greater than the width of said slideway, and said bore in said web being located in alignment with the central portion of said slideway and in alignment with

45 the path of force transmission between said head portion and said slideway.

4. A piston comprising a head portion and an encircling, depending, skirt portion, a web depending from the inner face of said head portion so as to extend longitudinally of the piston, a bearing block slideway supported from the free end of said web and arranged to extend transversely of said skirt portion but disconnected

50 therefrom, said web having enlarged portions adjacent each side thereof extending concentrically within and connected to said skirt portion and providing the only contact between said head and said skirt portions, said enlarged web side portions extending along the periphery of the piston skirt portion for distances no greater than the width of said slideway.

5. A double ended piston comprising spaced, opposed, substantially cylindrically shaped, head portions and an intermediately arranged, hollow, cylindrically shaped piston head encircling skirt portion, an axially extending web element projecting from the inner opposed faces of each head portion, each web element at its free end supporting a bearing block slideway that includes a

70

75

bearing surface arranged to extend transversely of and to be disconnected from the piston skirt portion, the opposed bearing block slideways being arranged in alignment with but spaced from each other, each web element including an opening that extends longitudinally of the associated slideway in a region adjacent thereto to provide means to increase the flexibility of the longitudinally extending central portion of the associated slideway, each end of each web portion having circumferentially extending portions connected to the adjacent piston skirt portion and providing the only connection between the piston head portions and the piston skirt portion.

6. A double ended piston comprising a pair of spaced, opposed, substantially cylindrically shaped, head portions, an intermediately disposed head encircling, hollow, substantially cylindrically shaped, skirt portion, a relatively narrow web portion depending from the inner surface of each head portion extending longitudinally of the piston, a relatively wide bearing block slideway supported by the inwardly disposed free end of each web portion, each slideway including a bearing surface that extends transversely of the piston skirt portion, the connection of each web portion to the associated slideway being in alignment with the longitudinally extending central portion of each slideway, an opening extending through each web portion in a direction lengthwise of the slideway in alignment with the connection of the web portion to the slideway, and portions on the opposite ends of each web portion connected to relatively small, diametrically opposed, portions of the piston skirt portion to provide the only connection between the piston skirt portion and the piston head portions.

7. A double ended piston comprising a pair of spaced, opposed, substantially cylindrically shaped, head portions, an intermediately disposed, head encircling, hollow, substantially cylindrically shaped, skirt portion, a relatively narrow web portion depending from the inner surface of each head portion extending longitudinally of the piston, a relatively wide bearing block slideway supported by the inwardly disposed free end of each web portion, each slideway including a bearing surface that extends transversely of the piston skirt portion, the connection of each web portion to the associated slideway being in alignment with the longitudinally extending central portion of each slideway, and portions on the opposite ends of each web portion connected to relatively small, diametrically opposed, portions of the piston skirt portion to provide the only connection between the piston skirt portion and the piston head portions.

8. A double ended piston comprising spaced apart, opposed, substantially cylindrically shaped, head portions connected by an intermediately disposed, hollow, head encircling, substantially cylindrically shaped, skirt portion, a relatively narrow web portion extending longitudinally of the piston from the inner face of each head portion, each web portion having at its inwardly disposed free end a bearing block slideway that extends transversely of the piston skirt portion, each slideway being aligned with and spaced from the slideway carried by the web of the other head portion, each web portion having an integral, interiorly disposed strut member that extends longitudinally thereof substantially between the outer face of the piston head and the slideway carried thereby, said strut extending transversely of the head web the full distance be-

tween diametrically opposed portions of the piston skirt and having portions at each end thereof connected to said diametrically opposed portions of the piston skirt, said last mentioned portions of the strut providing the only connection of the piston head to the piston skirt portion.

9. A double ended piston comprising spaced apart, opposed, substantially cylindrically shaped, head portions connected by an intermediately disposed, hollow, head encircling, substantially cylindrically shaped, skirt portion, a relatively narrow web portion extending longitudinally of the piston from the inner face of each head portion, each web portion having at its inwardly disposed free end a bearing block slideway that extends transversely of the piston skirt portion, each slideway being aligned with and spaced from the slideway carried by the web of the other head portion, each web portion having an integral, interiorly disposed strut member that extends longitudinally thereof substantially between the outer face of the piston head and the slideway carried thereby, said strut extending transversely of the head web the full distance between diametrically opposed portions of the piston skirt and having portions at each end thereof connected to said diametrically opposed portions of the piston skirt, said last mentioned portions of the strut providing the only connection of the piston head to the piston skirt portion, said strut member having an enlarged portion at the inwardly disposed end thereof with an opening therethrough extending transversely of the head web adjacent the connection of the web to the slideway, said opening being aligned with the longitudinally extending central portion of the slideway.

10. A piston as set forth in claim 9 wherein the outwardly disposed end of the strut member adjacent the outer face of the associated piston head has an enlarged anchor portion formed thereon.

11. A piston as set forth in claim 10 wherein the enlarged anchor portion of the strut includes slotted formations extending transversely thereof.

12. A piston as set forth in claim 9 wherein the portions on the strut ends that are connected to the piston skirt comprise wing-like flanges that extend only a limited peripheral distance around the piston skirt.

13. A piston as set forth in claim 9 wherein the strut includes transversely extending apertures that are adapted to receive portions of the piston head material to provide a means for anchoring the strut in the piston head.

14. A piston as set forth in claim 9 wherein there is a second web member extending, longitudinally of the piston from the inner face of each piston head, said second web being arranged at an angle to the first mentioned web and being connected to the associated slideway.

15. A double ended piston comprising spaced apart, opposed, substantially cylindrically shaped, head portions of aluminum or similar high thermal conductivity material connected by an intermediately disposed, hollow, head encircling, substantially cylindrically shaped, skirt portion of steel or similar low thermal conductivity material, a relatively narrow integral web portion extending longitudinally of the piston from the inner face of each head portion, each web portion having at its inwardly disposed free end a bearing block slideway that extends transversely of the piston skirt portion, each slideway

11

being aligned with and spaced from the slideway carried by the web of the other head portion, each web portion having an integral, interiorly disposed strut member of steel or some similar low thermal conductivity material that extends longitudinally thereof substantially between the outer face of the piston head and the slideway carried thereby, said strut extending transversely of the head web the full distance between diametrically opposed portions of the piston skirt and having enlarged portions at each end thereof connected to said diametrically opposed portions of the piston skirt, said last mentioned portions of the strut providing the only connection of the piston head to the piston skirt portion, said strut member having an enlarged portion at the inwardly disposed end thereof with an opening therethrough extending transversely of the head web adjacent the connection of the web to the

12

slideway, said opening being aligned with the longitudinally extending central portion of the slideway and providing a heat dam to block the flow of heat to the associated slideway from the associated head portion.

JOHN P. BUTTERFIELD.
